Marshall R. Chambers, 5070 Deepwood,
Bloomfield Hills, Mich.

Filed Aug. 22, 1961, Ser. No. 66,456

Term of patent 14 years

(Cl. D52—6)

FIG. 1 is a front elevational view of a fluid pressure test gage embodying my new design;

FIG. 2 is a side elevational view;

FIG. 3 is a top view;

FIG. 4 is a sectional view taken on the line 4—4 of FIG. 2; and

FIG. 5 is a bottom view.

It is to be understood that the ornamental surface shown is continuous throughout the cylinder.

I claim:

The ornamental design for a fluid pressure test gage, substantially as shown and described.
